UNITED STATES PATENT OFFICE.

CARL B. PARSONS, OF DETROIT, MICHIGAN, ASSIGNOR TO PARSONS MANUFACTURING COMPANY, OF DETROIT, MICHIGAN, A CORPORATION OF MICHIGAN.

DELIVERY-BODY.

1,359,734.

Specification of Letters Patent. Patented Nov. 23, 1920.

Application filed July 25, 1919. Serial No. 313,276.

all whom it may concern:

Be it known that I, CARL B. PARSONS, a citizen of the United States, residing at Detroit, in the county of Wayne and State of Michigan, have invented certain new and useful Improvements in Delivery-Bodies, of which the following is a specification.

This invention relates to delivery body doors and has for its object a delivery body door and hinge which permits the use of one or more doors inside the rear posts of the body but which can swing around through three-quarters of a turn into a position parallel to the side of the body. It is very desirable to have the doors of a delivery wagon swing clear around against the side of the body instead of through half a turn at a position at right angles to the body where they are very liable to be in the way of traffic. It is also desirable to have the door inside of the rear posts of the body as it makes a very much neater looking appearance.

In the drawings,—

Figure 1 is a horizontal cross section of the rear of a delivery body and showing how the doors are hung.

Fig. 2 is a perspective of the hinge.

Fig. 3 is a fragmentary perspective of the hinge showing how the wings are reinforced.

Fig. 4 is an enlarged fragmentary view of the rear post and door of the delivery body showing how it is hung.

Delivery bodies as at present constructed usually have the ordinary butt hinge. This, on a door set inside the rear posts, allows the door, to turn only through half a turn so that when it is at its limit of opening it is projecting perpendicularly to the sides of the body. In this position, if it is struck from the rear by traffic, it is bound to tear the door off from the hinges. With my special form of hinge the door is capable of swinging clear around parallel with the sides of the body.

In the drawings *a* designates the side of the body; *b* the rear door post; *c* the doors, which as indicated in Figs. 1 and 4, are set inside of the rear door post. The hinge is fastened to the inside of the door post by the anchor plate *d*. *e* is a narrow continuation of the anchor plate perpendicularly thereto adapted to connect with the

knuckle and which will be designated the stationary web. *f* designates the L-shaped wing adapted to be screwed to the door *c*. This is provided with a narrow extension *g* which connects the wing with the knuckle and which will be designated the swinging web. Although this is an integral part of the wing *f* it is given a separate designation because it does not lie directly up against the door to which the wing is attached but serves to connect the wing proper with a remotely placed knuckle *i*. The knuckle is formed in the usual way by notching and rolling up the ends of the two webs but the knuckle is bent over at a sharp angle toward the front and lies at the front of the rear plane of the rear post, as is clearly shown in Fig. 4.

A special reinforcement, which consists in dishing the swinging web and the wing *f*, as is shown in Fig. 2 at *h*, and dishing the stationary web *j* as shown in Fig. 3, permits this hinge to be made as a stamping of relatively light metal and still have strength enough to be durable.

By placing the anchor plate on the inside of the door post a relatively long anchor plate can be utilized and yet be concealed. The anchor plate can be made almost as long as desired, thereby effecting a much more secure support.

The dishing of the swinging web *g* and the wing *f* is roughly in the form of a Y but it enables this corrugating of the metal to not only strengthen the connecting web but those portions of the wing which are adjacent and which bear the major part of the load. The dishing of the anchor connecting web *e* is slightly smaller than the dishing of the swinging web *g*, as shown in Fig. 3, so that the two corrugated parts can nest one within the other.

What I claim is:

The combination of a delivery body provided with rear door posts, one or more doors for closing the opening formed by the rear door posts, the said door or doors set inside of the rear door posts and adapted to swing around to a position parallel with the side of the body, and supports for said door or doors comprising hinges, each of which is provided with a stationary web running across the rear face of the door post, and an

anchor plate substantially perpendicularly arranged with respect to the stationary web and which is secured to the inside of the door post, a knuckle secured to the stationary web projecting beyond the side of the door post at the outside corner, a wing fastened to the rear face of the door, and a con-

tinuation of the wing beyond the edge of the door which forms a web running across the rear face of the door post when the door 10 is closed and overlapping and contacting the said stationary web when the door is closed.

In testimony whereof I affix my signature.
CARL B. PARSONS.
